COSMETIC DEVICE

Leon H. Amdur, Brooklyn, N. Y.

Application August 4, 1938, Serial No. 223,040

35 Claims. (Cl. 132—82)

This invention, which relates to cosmetic devices, has for its objects the following: a simple, inexpensive and practical applicator for face powder or rouge of the type which is self-contained, the container serving as a handle when the applicator is propelled and exposed for use; a self-contained cosmetic device in which the applicator is a pad, rather than a powder puff; a self-contained powder or rouge applicator of one-piece construction having no separable or hinged cap member; a powder or rouge device which is normally completely closed and which is opened by the same movement of a manipulative member which propels and exposes the applicator; a combined powder and rouge device; a combined cosmetic device in which a single applicator is used for both powder and rouge; a combined and self-contained powder and rouge applicator device; a device of the class described in which one face of the applicator is used for face powder and the other face, for rouge; a self-contained face powder device having a pad applicator and a powder compartment, the applicator being powdered from the compartment when the applicator is retracted; a cosmetic device in which a powder pad applicator is self-contained and automatically powdered; a self-contained cosmetic device provided with a cosmetic cake which is capable of daubing the applicator when the applicator is retracted; a cosmetic device in which an applicator is self-contained and daubed; a combined powder and rouge device in which an applicator is self-contained and powdered on one side and daubed with rouge on the other; a combined cosmetic device comprising a self-contained applicator, a powder compartment and a rouge cake for powdering and daubing respective faces of the applicator; a powder device having a powder compartment and a self-contained applicator propellable through an open end of the device normally closed by a closure member which is also adapted to open the powder compartment when the device is closed and to close the compartment when the applicator is in propelled operative position; a powder device having a propellable applicator and a powder compartment which is open when the applicator is retracted and closed when the applicator is propelled; a self-contained device provided with a powder chalk which is capable of powdering the applicator when retracted; a combined powder and rouge device comprising a powder chalk and a rouge cake and an applicator one face of which is powdered from the chalk and the other face, daubed from the rouge cake; a cosmetic

device having a cosmetic cake and an applicator and the provision of controlled daubing of the applicator by the cosmetic cake; a cosmetic device having a single applicator and double compartments for face powders of different shades; a cosmetic device having a single applicator and a pair of cosmetic cakes of different shades; a cosmetic device having a retractable pad applicator and a replenishable powder compartment for automatically powdering the said applicator when retracted; a self-contained cosmetic device having a replaceable applicator; a self-contained cosmetic device having a retractable applicator and a replenishable rouge cake for daubing the same; a combined cosmetic device having a face powder applicator, a rouge applicator and a lipstick; a cosmetic device having an applicator having a powder face and a rouge face, and a lipstick; a cosmetic device comprising a retractable applicator, a replenishable rouge cake for daubing the applicator, and a lipstick unit for holding the cake in place; a cosmetic device of the class described made of one-piece construction; a cosmetic device of the class described, which may be held and manipulated in one hand, the other hand being free to hold a mirror.

For the attainment of these and such other objects as may hereinafter appear or be pointed out, I have shown an exemplification of one form of my invention in the accompanying drawing, in which:

Fig. 1 is perspective view of one form of a complete device of this invention;

Fig. 2 is a sectional longitudinal view thereof taken on a diameter from left to right; 35

Fig. 3 is likewise a sectional longitudinal view but taken on a diameter from front to back;

Fig. 4 is a top view of the device;

Fig. 5 is a section through the device on the line 5—5 of Fig. 3; 40

Fig. 6 is likewise a section through the device but on the line 6—6 of Fig. 2;

Fig. 7 is a sectional elevational detail of a modified form of impositive connection between the slide and the shutter; and 45

Fig. 8 is a bottom view of the device.

The cosmetic device of this invention and which will achieve the objects above set out is housed within a casing 1 which is open at both ends and conveniently formed from sheet metal 50 stamped to the required formation and the edges brought together and sealed in any suitable manner (to enclose certain other parts which will be presently described). The casing 1 may be of any desired sectional outline, either flat or circular, 55

although the figures, see esp. Figs. 5 and 6, show the latter, for illustrative purposes. The circular section in the figures, see Figs. 5 and 6, is disrupted by a pair of diametrically opposed flutes 5 or wide channels 2 and 12 which extend substantially the entire height of the casing, see Fig. 1, (the purposes of these flutes will subsequently be explained). The casing is not entirely cylindrical, as can best be seen from Figs. 1 and 3, because 10 of a taper 11 and 11' given to the front and rear opposed walls of the upper portion of the casing, which taper towards an opening 8 at the top of the casing.

Extending the entire length of the casing is a 15 member which serves a number of functions but which for convenience will be simply referred to as the frame member. The frame member is in the form of an elongated U-shaped member, the front leg of which is designated 20 and the 20 rear leg designated 20', Fig. 3. The bend of the U, designated 21 extends somewhat through the top opening 9 of the casing 1. The frame member is formed from a single sheet of material, the edges of which (before the member is given the 25 U-shape) are folded in to form side flanges; the left flange of the front leg 20, as viewed in Fig. 6 looking from front 20 to rear 20', is designated 22, while the right flange of front leg 20 is designated 23. The left flange of the rear leg 20' of 30 the frame member, still viewing Fig. 6 in the same manner, is designated 22' and the right flange, 23'. The web portion of the front leg 20 is designated 24 and the web of the rear leg 20' is designated 24'.

35 One of the purposes of providing the pair of flutes 2 and 12 already referred to, is to position the frame member, or rather its left and right legs, firmly in place in the casing, which is done by crimping the casing material along the 40 flanged edges of the frame member in the manner clearly seen in Fig. 5.

The web portion of the frame member is provided at the bend 21 with a cut-out 25, through which is propelled the powder and/or rouge applicator, later fully described.

45 In the central portion of the casing, within the space between the two legs of the frame member, is provided a slide designated 30, and which may be formed of two pieces of sheet material, a front piece 31 and a rear piece 31' formed 50 as best shown in Fig. 6. The ends of the pair of pieces 31 and 31' are brought together as clearly shown in Figs. 6 and 5, to form manipulative lugs 32 and 33. The casing, more particularly, 55 the innermost portions of the flutes 2 and 12, is provided with slots 3 and 13, respectively, for the lugs 32 and 33. The exposed ends of the lugs are knurled or serrated or otherwise formed to provide finger gripping portions. By means of 60 the lugs, the slide may be moved from the lower end of the slots, its position as shown in solid lines in Fig. 2, to the upper position shown in dot-and-dash lines in the same figure.

The slide may be manipulated from retracted 65 to propelled position or vice versa, by the use of but one lug, so that the device may be operated by one hand; this is desirable to free the other hand for holding the mirror usually required to inspect the face as the cosmetic is applied. Single 70 hand operation is possible, using either one or the other of the two lugs, or the device may be provided with but a single lug.

75 One of the functions of the slide is to propel and retract the applicator, which, designated 76 generally 40, is attached to the slide in a manner

presently described. The applicator comprises a piece of suitable textile, fibre or other material, designated 41, processed in a suitable and known manner, to form pleats designated 41a, 41a', to 5 41d, in Fig. 5. When the slide is in its lower position and the applicator retracted within the casing, the applicator material 41 is folded up as shown in Fig. 5, presenting folded edges 41a, 41b, 41c and 41d to the front of the device and edges 41a', 41b', and 41c' to the rear. It is clear that 10 these number and arrangements of folds may be varied as desired. In any event, as the slide is pushed upward and the applicator propelled from the casing, the applicator material spreads or fans out from the contracted condition of Fig. 15 5 to the open and extended condition of Fig. 2 to present a sufficient wide cosmetic applying surface. The applicator (41) may be cheaply made, using ordinary flat material in which pleats have 20 been processed as by pressure and steam, etc. 25 Or the pleats or folds may be pre-fabricated in the material. The side edges of the material 41 is secured in a suitable manner to arms 44 and 45, which are preferably formed of narrow sheet material folded in the form of a U, the respective side edges of the applicator material inserted therein, and the U-sheet metal crimped together to hold the edges of the applicator material securely therein, see esp. Fig. 5. The edges of the arms thus present a metallic wearing surface to 30 the edges of the open portion of the shutter, i. e., to the edges of the shutter straps 56 and 57 of the shutter or closure member more fully described presently, and to the edges of the flanges 22, 22', 23, 23', and thus shield the applicator 35 material from wear. By tapering the portion of the casing near its open end, designated 11 and 11', as already described, toward the casing opening, the otherwise right angle corners are removed (which might have the effect of holding 40 off the flat applicator from the face) and the device may be brought closer to the face and more easily handled.

For the purpose of pivotally (and replaceably) 45 mounting the pair of arms 44 and 45 to the slide 30, the slide is provided with a pair of upstanding supports, respectively, 34 and 35. The upper ends of the supports are turned upon themselves to form eyelets 42 and the central portion of the supports, e. g., support 34 shown in Fig. 3, is 50 cutaway 43, Fig. 3, leaving a pair of eyelets on each support; the eyelets of support 34 are designated in Fig. 3 as 42 and 42'. The eyelets of support 35 are similarly designated in Fig. 6. The lower portions of arms 44 and 45 are spread somewhat apart (see arm 44 in Fig. 3 and arm 45 in Fig. 6) to make them more springy, and each arm is provided with a pair of short studs or cylindrical lugs 46 and 46', see Fig. 3 and Fig. 6, which fit in the eyelets of the support, respectively, 42 and 42'. Arm 44, for example, is attached to its support 34 by squeezing together the end of the spread-apart arm and forcing the end between the eyelets 42 and 42' until the lugs or 55 short studs 46 and 46' snap into the eyelets 42 and 42'. Arm 45 is attached in the same manner to support 35.

Between the arms 44—45 is provided a suitable spring, such as the piece of spring wire 47, the ends of which are attached to the arms, as 70 by the same or a similar crimping operation by which the applicator material is secured to the arms. The natural tendency of spring wire 47 is to separate its two ends. In retracting the slide and applicator to the position shown in Fig. 75

2, the spring is tensioned by forcing the ends of the wire toward each other. As the slide is pushed forward and the arms (together with the applicator material) propelled through the 5 cutout 25 in the frame member 20 (likewise, opening 9 at the top of the casing), the arms are spread apart by the tensioned spring to the dot-and-dash position of Fig. 2. As the slide is pushed downward, the arms are forced or squeezed 10 together—the applicator material folding into the pre-arranged pleats—against the force of spring 47.

The slide 20, its supports 34 and 35, and the arms 44 and 45 also serve to close the slots 3 and 15 13 (required for finger lugs 32 and 33 of the slide). Support 34 and arm 44 (under pressure of spring 47) close slot 3, see Fig. 2, while support 35 and arm 45 (also pressed by spring 47) close slot 13. That is, these slots are closed when the 20 device is closed with the applicator retracted.

A further function of the casing flutes 2 and 12 may now be pointed out and that is, the innermost edges of the flutes serve to maintain the arms 44 and 45 of the retractable applicator in 25 alignment with the inside edges of the straps 56 and 57 of the shutter 50 (which will be presently described) and also within the inside edges of flanges 22, 22', 23 and 23' of the frame member, which define the opening through which the 30 applicator clears, so that the arms will encounter no overhang to block their emergence from the casing.

There may be provided at the bend or topmost portion of the track member, see Fig. 2, a pair of 35 seats 14 and 15 respectively, cooperating with arms 44 and 45, to provide abutments for the arms which are pressed apart by the spring 47. The arms may be provided with recessed portions forming shoulders 48 and 49 which snap over the 40 respective seats 15 and 14, to hold the applicator in extended position and to hold its pair of arms more firmly.

The opening 25 in the frame member through which the applicator is propelled, is normally 45 closed—i. e., when the applicator is retracted—by a thin, flexible closure or shutter 50 which is guided in the trackway of frame member 20. It is thus seen that one of the functions of the frame member 20 is to provide a trackway for the shutter 50 which it does by the provision of the turned-in edges or flanges 22 and 23 and 22' and 23' already described.

Closure shutter 50 may be operated by the slide 20; the shutter 50 may be positively secured to the slide as shown in Fig. 3, or the connection between the slide and shutter may be an impositive one, as shown in Fig. 7. Taking up first the structure of Fig. 3, the shutter is secured at 51 near its trailing end 52 (at the front 55 of the device, Fig. 3) to the front piece 31 of the slide. The portion of the shutter which serves to close the aperture 9—25, extends from the leading end 53 of the shutter to a point designated 54; the aperture closing portion of the 60 shutter will be referred to as 53—54. The shutter is provided with an open portion which extends from point 54 to a point designated 55, see Fig. 3. The width of the open portion 54—55 is from the inner edge of flange 22, see Fig. 5 to the inner 65 edge of flange 23, of the frame member; hence there is from point 54 to point 55, Fig. 3, a shoulder strap 56 and 57, Fig. 5, along both edges of the opening 54—55.

In the lower position of slide 20 as shown in 70 Fig. 3, with the applicator retracted within the

casing, the casing opening 9—25 is closed by the aperture closing portion 53—54 of the shutter. As the slide is pushed upwardly, the shutter which is secured to the slide as already described, is advanced along the trackway of the frame member 75 5, the closing portion 53—54 of the shutter moving (clockwise, as viewed in Fig. 3) away from casing aperture 9—25, the opening 54—55—56—57 of the shutter traversing across the casing aperture. It will be observed from Fig. 3 10 that the top of the applicator 40 when in retracted position (as shown in that figure) is sufficiently below the bend 21 of the frame member, so that the closing portion 53—54 of the shutter will have been advanced away from the casing 15 aperture 9—25 when the top of the applicator reaches the aperture; hence further movement of the slide will propel the applicator through the shutter opening 54—55—56—57. The latter opening is sufficiently long 54—55 so that the 20 applicator may project therethrough as the shutter continues to be advanced by the slide.

The impositive connective construction between the slide and the shutter is shown in Fig. 7, wherein the slide is designated 130, its front 25 piece 131; the frame member or rather the web of the front leg thereof is designated 120. The shutter 150 is likewise as in Fig. 3, made of thin, flexible material. The proportion of the shutter which is imperforate (for closing the casing aperture) and which is open (for applicator propulsion) is different than in the construction of Fig. 3. In the modification of Fig. 7, the shutter open portion is very much smaller, and need only be sufficient for the applicator to pass through; this 30 results from the fact, as will be more fully explained presently, that the shutter remains immobile while the applicator is being propelled from the casing.

The end 152 of shutter 150 is secured to an 40 auxiliary slide 100, which is guided for an extent of sliding movement between the web 120 and edge flange 122 of the frame member. It will be observed from Fig. 7 that a sufficiently wide space is provided between web 120 and flange 122 for 45 the thickness of auxiliary slide 100, and that the space between the upper portions of the web and its flange, designated 120' and 122' in Fig. 7, is merely sufficient for the thin shutter 150. A tab 158 is struck from the web 120 of the frame member to form a lower stop limiting the downward movement of auxiliary slide 100; a similar tab 159 constitutes the top stop, so that auxiliary slide 100 is vertically movable between stops 158 and 159. Auxiliary slide 100, and shutter 150 secured thereto, are raised and lowered by manipulative slide 130 through the provision of a spring member 110 which is looped in the manner shown and having one end 111 secured to the inside of the front piece 131 of the manipulative slide 130. 50 Front piece 131 is provided with a slot 132 through which passes the end of the spring member 110, which end is beveled (112) for a purpose soon apparent. The member 110 is constituted to put its bevel end 112 under spring tension tending to 55 project that end through slot 132 of the manipulative slide 130. Member 110 is provided with a stop 113 limiting the extent of projection of spring end 112.

Bevel end 112 of spring member 110 is receivable in a depression or cup 101 provided in auxiliary slide 100. When the manipulative slide 130 is in its lowermost position as shown in Fig. 7 with the applicator retracted and the casing aperture closed, the end 112 of spring member 75

110 is positioned in cup 101 of the auxiliary slide 100. Hence as the manipulative slide 130 is pushed upwardly, auxiliary slide 100 is advanced from its lower stop 159, in the same upward direction. This raising of auxiliary slide 100 moves the shutter 150, which is attached thereto, in a direction to open the casing aperture 9-25 (not shown in Fig. 7, but see Fig. 3). The upward movement of the auxiliary slide 100, spring end 112 still fitted in cup 101, continues until auxiliary slide 100 reaches upper stop 158, at which time the casing aperture is fully uncovered and the top of the applicator ready to emerge therethrough. Further upward movement of the manipulative slide 130 (to propel the applicator through the now opened casing) causes bevel end 112 of the spring member 110, the auxiliary slide 100 abutting upper stop 158, to leave depression 101 of the auxiliary slide. The manipulative slide 20 thus leaves the auxiliary slide, and continues its upward applicator-propelling movement. The bevelled end 112 of spring 110 snapping out of bevel hole 101, as described, enters an elongated slot 102 likewise provided in auxiliary slide 100. 25 A suitable detent may be provided to hold auxiliary slide (and the shutter) in advanced position to keep the casing open while the applicator is being propelled therefrom; for instance, the trackway 120-122 may be slightly pinched together to provide frictional engagement to hold the auxiliary slide.

In retracting the applicator, by downward movement of manipulative slide 130, the auxiliary slide 100 remaining in elevated position (against upper stop 158), bevelled end 112 of the spring member clears in elongated slot 102 of auxiliary slide 100. At the time the applicator has been fully retracted in the casing, the bevelled end 112 of the spring 110 of the manipulative slide abuts 35 the upper bevel edge of bridge 103 between elongated slot 102 and cup 101; continued downward movement of manipulative slide 130 now moves auxiliary slide 100 downwardly so that shutter 150 will close the casing aperture. Slide 100 continues to move downward until it abuts lower stop 159. Slide 100 itself is provided with a stop 40 104. As auxiliary slide 100 is stopped by 159, manipulative slide 130 continues downward until stopped by 104, the bevel end 112 of the spring 45 snapping out of the elongated slot 102 into cup 101. The parts are thus in position shown in Fig. 7 ready for opening manipulation of the device as already described.

The structure shown in Fig. 7 featuring the 55 impositive connection between the manipulative slide and the closure shutter may be used for other cosmetic devices in which, instead of an applicator (as illustrated in the other figures of this application), a cosmetic such as a lipstick 60 pencil or the like may be mounted on the slide for propulsion and retraction therewith.

If desired the shutter may be entirely independent of the applicator slide. It may, for example, take the form of a thin shutter which may be 65 moved by finger pressure from closed to open position and vice versa. Or any other suitable closure means may be used, such as a removable lid or cap.

The device (thus far described) may be used 70 merely as a pad or applicator or spreader or the like, without provision for supplying the applicator with face powder or rouge or similar cosmetic.

From another aspect my invention contemplates self-contained and automatic provisions for 75 supplying a face pad or applicator, such as the

self-contained applicator already described, with face powder, rouge or similar cosmetic. The device illustrated in the drawing is implemented with a face powder compartment 19 between the casing 1 and the frame member (front leg) 20 or rather its web 24, which thus serves as a powder partition. The lower portion 29 of the frame member, or rather the front leg 20 thereof, see Fig. 3, is sloped toward the rear leg which it joins to form a sort of powder-tight funnel; the purpose of thus funnelling out the bottom portion of the powder partition is to provide a wide mouth 4 at the bottom end of casing 1, for replenishing the compartment with fresh powder and to provide clearance for closure plug 18.

Closure plug 18 is provided with screw threads 17 screwing into threads 7 tapped into bottom cap 8 which is secured, by soldering or similar permanent fastening means, in the bottom open mouth 4 of the casing to provide a permanent 20 end closure for the casing. As seen in Fig. 8, the plug 18 is provided with a recess or groove 16 in which may be inserted a thin coin or tool for unscrewing the plug. In this manner access may be had to the powder compartment for the purpose of replenishing it with powder or other purposes.

Communication is afforded between the powder compartment 19 and the applicator 40, or rather the applicator material 41, by the provision of a 20 plurality of holes 26 in the front web 24 of the frame member. Powder contained in compartment 19 will thus coat itself, through holes 26, upon the applicator. As shown in Fig. 5 the partition holes 26 may be aligned with the folds 35 (41a, 41b, etc.) of the applicator. It will be readily understood that the applicator material, in its folded, retracted and squeezed condition, serves to close the powder openings; by aligning the partition holes with the folded edges of the 40 applicator, the latter will more tightly close the powder ports. Instead of a plurality of powder openings, such as 26, a single large opening (not shown) may be provided in the partition to put the powder compartment in communication with 45 the applicator. However, the plurality of holes serve as a sifter for the powder, and might be preferred for this reason.

It is thus seen that when the applicator is retracted and the shutter 50 closes the casing aperture 9-25, the powder ports 26 are closed by the applicator material 41 itself, which thus becomes coated with face powder. When the slide 30 is pushed upward to open the casing aperture and to propel the applicator, the latter will have powder supplied to one side thereof (i. e., to the face of the applicator corresponding to folds 41a to 41d, Fig. 5). When the device is being used, i. e., with the applicator in extended spread-out condition (dot-dash lines, Fig. 2), the applicator no longer serves to close the powder ports. There is no imperative need for closing these ports when the device is being applied to the face, since in this operation the casing is held substantially vertical and the powder will fall to the bottom 60 of the compartment, at least below the lowest powder port 26, the compartment, of course, never being completely filled with powder. But if it is desired to close the powder ports 26 when the applicator is in projected position, this may 65 conveniently be done by the shutter member 50. As the slide 30 is being elevated and the applicator 40 moved away from the ports and out of the casing, the imperforate part of the shutter 50, starting from point 55, Fig. 3 and extending 70

to trailing point 52 of the shutter, comes in front of the powder ports 26 to effectively close these ports. This may be achieved by the shutter 50 of the form shown in Fig. 3 or by the shutter 150 of the modification shown in Fig. 7.

It may be desired to provide an adjustment for the size of the powder ports, so as to regulate the amount of powder supplied to the applicator; this is shown in Fig. 3 and comprises a shield member 38 slidably mounted in the powder compartment 18 by the provisions of slots 36 in the shield member and pins 28 projecting from partition 24. The upper portion of the shield member is provided with a plurality of elongated slots 36 which 15 cooperate with a corresponding plurality of elongated slots 26 in the partition 24. The lower extremity of the shield member is provided with a projecting lug 37 which may be readily reached through the opening at the bottom end of the 20 casing when plug 18 is removed. The shield member may thus be moved (vertically) to adjust the effective opening between the elongated slots 36 of the shield and the elongated slots 26 of the powder partition; when the two sets of slots are 25 in registry, the effective opening is at the maximum; by moving the shield slots away from registry the effective opening may be diminished as required.

The device illustrated in the figures is also 30 provided with facilities for supplying the applicator with rouge. As best seen in Figs. 3 and 5, the rouge is in cake form, the rouge itself being designated 60 and mounted on a backing 61 of suitable material; the rouge 60 together with its 35 backing 61 make a complete unit which may be replenished as such. The web 24' of the rear leg 20' of the frame member has a cut-out portion 27 affording communication between the rouge and the applicator or rather the top portion of the applicator material (more particularly, fold points 41a', 41b' and 41c', Fig. 5). Normally the rouge cake (60-61) is maintained 40 out of contact with the applicator by the provision of a pair of strip springs 68 and 69, the lower 45 portions of which are secured to the web 24' of the frame member; the upper portions of the springs bear against shoulders 62, 63 left on the backing by making the rouge cake 60 somewhat short, see Fig. 5. For the purpose of moving the 50 rouge toward the applicator to contact the same, a finger hole 5 is provided in the casing opposite the rouge backing 61. The finger hole is of less area than the backing (which incidentally is contoured to the inside bore of the casing, see 55 Fig. 5) so as to prevent the rouge unit from falling through the finger opening. By placing a finger at opening 5 and pressing against backing 61 thereat exposed, the rouge cake may be brought in contact with the applicator to daub 60 the same with rouge.

The rouge cake is maintained in position opposite to the port 21 in the frame partition and opposite to finger opening 5 in the casing, by means of a member 70 which may be itself a 65 cosmetic unit, such as a lipstick unit. Lipstick unit 70 is insertable in the space between the casing and partition 24' (20') of the frame member, through a hole 10 in the bottom cap 8, see Figs. 3 and 8, and is there maintained by the 70 plug 18, or rather the overhanging shoulder 18f of the plug, as clearly seen in Fig. 8. One portion of the plug periphery is flattened, 18f, so that by turning the plug—by the use of a thin coin or tool inserted in groove 16, as already explained,—75 flat 18f may be brought opposite the lipstick unit

70 so that no overhanging portion would prevent its removal or insertion.

The upper end of the lipstick unit is provided with an L-shaped hook comprising an upright leg 74 and a horizontal leg 75. A recess 64 is 5 provided at the rear of backing 61, for the vertical leg 74, and a slot 65 is provided through the backing, for horizontal leg 75. Prior to inserting the rouge cake 60-61 and the lipstick unit 70 in the casing, the former is positioned on the 10 hook by passing hook leg 75 (horizontal) through the backing slot 65. The rouge cake, thus coupled to the lipstick unit, is thrust into the casing, together with the lipstick unit which is thus instrumental in moving the rouge cake ahead of 15 it and against the springs 68-69 until the cake 60 is finally opposite port 27 and backing 61 is opposite finger hole 5, at which time, the lipstick unit will be completely within the casing; the plug 18 is then turned to lock the parts in 20 place as described. It is observed in Figs. 6 and 3 that the upper portions of the lipstick unit is cutaway 78, 79, to provide clearance for the springs, respectively 68 and 69.

The lipstick unit may be of any desirable construction, and may be manipulated as by a knob 76 clearing through a slot 6, see also Fig. 1, provided in the casing 1; the downward movement of knob 76 is effective to propel the lipstick pencil out of the bottom, Figs. 3 and 8, of the 30 unit. The particular closure device for the lipstick unit may take any desired form; the lipstick pencil may merely project from the unit or it may be entirely removable therefrom when used on the face. Or, the lipstick unit may be eliminated and merely a block or holder 70 be used for holding the rouge cake, and having no cosmetic function of its own.

The applicator 40, or rather its applicator material, serves both as a face powder medium and 40 as a rouge medium, one side of the material, the front side (41c, 41b, 41c and 41d, Fig. 5) serving for the face powder and the other side (41a', 41b' and 41c', Fig. 5) for the rouge.

It is clear that the device need not be arranged 45 and provided (with face powder, rouge and lipstick) as shown in the figures. A wide diversification of facilities and arrangements are possible and contemplated within the invention, among which may be enumerated: a device provided 50 merely with an applicator or pad (puff); a device provided with an applicator plus a single powder compartment; an applicator device provided with two powder compartments, for face powders of different shades and/or textures. In the arrangement last suggested the leg 20' and web 24' of the frame member and the shutter would be 55 constructed, similar to the construction shown in Fig. 3, so that the powder ports of both powder compartments will be closed when the applicator 60 is propelled from the casing. Further arrangements would be: a device provided with an applicator and a rouge cake; an applicator device provided with a rouge cake and a lipstick; an applicator device provided with two rouge cakes of 65 different shades; the latter further provided with a lipstick or lipsticks of different shades; an applicator device provided with powder compartment and rouge cake; the latter further provided with a lipstick or lipsticks of different shades; an 70 applicator device provided with powder compartment and rouge cake; the latter further provided with a lipstick (this is the arrangement shown in the drawing).

Instead of loose powder, a powder chalk may 75

be used, in which case the construction shown and described in connection with rouge cake 60-61 may be used. Hence other arrangements might be: a device provided with an applicator 5 and a powder chalk; the same further provided with a lipstick; an applicator device provided with two powder chalks of different shades and/or textures; an applicator device provided with a powder chalk and a rouge cake; the last two 10 further provided with a lipstick or lipsticks. It is clear that a lipstick unit can only be used with the rouge cake or with the powder chalk. Instead of the supporting unit 70 being a lipstick, it may be any other desired cosmetic item, 15 such as an eyebrow pencil, an orange stick and so forth. An arrangement of four different cosmetic items conveniently arranged in a self-contained unit might be mentioned and that is an applicator device provided with powder chalk, 20 rouge cake, lipstick and eyebrow pencil.

I claim:

1. In a device of the class described, the combination of a casing open at one end and provided with a powder compartment, an applicator contractible to the confines of the said casing and spreadable to present a cosmetic applying surface, closure means for the said casing opening and the said powder compartment, and manipulative means effective upon movement in one direction 30 to close the powder compartment and to move the casing closure means to open position and to propel the powdered applicator through the casing opening, and effective upon movement in the opposite direction to retract the applicator within 35 the casing and to open the powder compartment and to move the casing closure means to closed position.

2. In a device of the class described, the combination of a casing open at one end, an applicator contractible to the confines of the said casing and spreadable to present a cosmetic applying surface, closure means for the said casing opening, and manipulative means for the applicator and the said casing closure means effective upon movement in one direction to move the closure means to open position and to propel the applicator through the casing opening to spread condition exterior of the casing and effective upon movement in the opposite direction to retract the applicator in contracted condition within the casing and to move the closure means to closed position.

3. In a device of the class described, the combination of a casing having a powder compartment, an applicator propellable from the casing to present a cosmetic applying surface, closure means for the said powder compartment, and manipulative means for the applicator and the closure means effective upon movement in one direction to propel the applicator from the casing and to close the powder compartment and effective upon movement in the opposite direction to retract the applicator and to open the powder compartment.

4. In a device of the class described, the combination of a casing, a pad applicator contractible to the confines of the said casing and retractable therein and spreadable to present a flat cosmetic applying surface, and a powder compartment in the casing for supplying powder directly to the exterior, cosmetic applying surface of the applicator when contracted and retracted within the casing, the said applicator being effective in retracted position to close the 75 said powder compartment.

5. In a device of the class described, the combination of a casing, a pad applicator contractible to the confines of the said casing and spreadable to present either or both of its two faces as a flat cosmetic applying surface, and 5 means for retracting the applicator in contracted condition within the casing and for propelling the applicator to spread condition exterior of the casing.

6. As a new article of manufacture for use 10 in the device, including a casing, of the class described, a pad applicator retractable within the casing and contractible to the confines thereof and propellable from the casing and spreadable to present a flat cosmetic applying surface. 15

7. In a device of the class described, the combination of a casing open at one end and provided with a powder compartment, an applicator propellable through the said casing opening and closure means for the casing opening 20 and the powder compartment actuated by movement of the said applicator.

8. In a device of the class described, the combination of a casing, an applicator retractable within the said casing and propellable therefrom, a powder compartment provided in the casing for powdering one face of the retracted applicator, and a rouge cake provided in the casing for daubing the other face of the retracted applicator. 30

9. In a device of the class described, the combination of a casing, an applicator retractable within the said casing, a cosmetic cake replaceably supported in the said casing out of contact with the applicator and adapted to be 35 moved into contact with the applicator to daub the same with cosmetic.

10. In a device of the class described, the combination of a casing, an applicator retractable within the said casing, and a cosmetic cake supported in the casing and spring pressed away from the said applicator, the said casing being provided with a hole for a finger whereby the said cosmetic cake may be moved in contact with the retracted applicator. 45

11. A new article of manufacture for use in the device, including a pair of springs, of the class described, a cosmetic cake comprising a supporting base for the cosmetic material which is set in from opposite edges of the said base to 50 provide shoulders thereon for the said pair of springs.

12. A new article of manufacture for use in the device, including a member having hook means, of the class described, a cosmetic cake 55 comprising a supporting base for the cosmetic material, the said base being provided with an opening for the said hook means.

13. In a device of the class described, the combination of a casing open at one end, a closure means therefor, a member mounted in the casing for an extent of sliding movement, a cosmetic element carried on the said slide member and movable therewith for propulsion from, and retraction within, the said casing, and an immobile connection between the slide member and the closure means whereby initial movement of the slide member in one direction will move the said closure means to open position and sustained movement of the slide member in the 70 same direction will propel the said cosmetic element through the opened casing, the said closure means remaining immobile in open position during the subsequent movement of the said slide member. 60

14. In a device of the class described, the combination of a casing open at one end, a frame member in the form of an elongated U, positioned in the said casing with the bend at the said casing opening, the edges of the frame member being folded-in to form a trackway, a flexible closure member slidable in the said trackway and provided with an opening, the width of which is substantially equal to the distance between the said folded-in edges of the frame member, and an applicator including a pair of hinged arms and spring means tending to spread the said arms apart, slidable in the space between the two legs of the said U-shaped frame member, the casing being provided with a pair of diametrically opposite flutes located centrally of the applicator space, the flutes being of sufficient depth to make the distance separating them substantially equal to the aforementioned width of the closure member opening, whereby the said pair of spring-pressed arms are confined to a distance apart equal to the said width of the opening of the closure member and may be propelled therethrough.
15. In a device of the class described, the combination of a casing open at one end, a frame member in the form of an elongated U secured in the casing with its bend at the said casing opening, the edges of the frame member being folded-in to form a trackway, and a flexible closure member for the said casing opening slidable in the said trackway, one leg of the said frame member serving as a partition forming a powder compartment between the casing and the said partition.
16. In a device of the class described, the combination of a casing open at one end, a section of the casing serving as a cosmetic space and another section serving as an applicator space, and an applicator including a pleated fabric propellable through the said casing opening to present the said fabric unfolded as a flat cosmetic applying surface and retractable within the casing with the said fabric folded in the said applicator space of the casing and presenting the folds at the said cosmetic space of the casing whereby cosmetic may be supplied to the applicator fabric.
17. In a device of the class described, the combination of a casing open at one end, a section of the casing serving as an applicator space and another section separated therefrom by a partition to form a powder compartment, and an applicator including a pleated fabric propellable through the said casing opening to present the said unfolded fabric as a flat cosmetic applying surface and retractable within the casing with the said fabric folded in the said applicator space and presenting the folds at the said powder compartment, the said partition being provided with communicative means between the powder space and the applicator space whereby powder may be supplied to the said folds of the applicator, the retracted and folded applicator being effective to close the said communicative means.
18. In a device of the class described, the combination of a casing open at one end and provided with a first cosmetic section, a second cosmetic section and an applicator section, and an applicator including a pleated fabric propellable through the said casing opening to present the obverse and reverse sides of the unfolded fabric as separate cosmetic applying surfaces, and retractable within the said casing with the fabric folded in the said applicator section to present the folds of the said obverse fabric side to the first said cosmetic section and to present the folds of the said reverse fabric side to the second said cosmetic section.
19. In a device of the class described, the combination of a casing open at one end, an applicator propellable therethrough and comprising a spring-pressed arm and a manipulative lug, the said casing being provided with a slot wherethrough the said applicator lug projects, the said spring-pressed arm being adapted when the applicator is retracted within the casing to close the said casing slot.
20. In a device of the class described, the combination of a casing having a closed bottom end and an open top end, an applicator propellable through the said open end, and a partition in the said casing defining a powder compartment, the said partition being provided with communicative means between the said powder compartment and the applicator, the said bottom being provided with a removable plug for gaining access to the said powder compartment.
21. In a device of the class described, the combination of a casing open at one end, an applicator propellable through the said casing opening to present a cosmetic applying surface and retractable within the said casing, a cosmetic cake, and means for positioning the said cake in the said casing relative to the said applicator whereby the said cake is adapted to daub the applicator with cosmetic.
22. In a device of the class described, the combination of a casing open at one end, a partition secured in the said casing, an applicator propellable through the said casing opening and retractable within the casing, a lipstick unit, a cosmetic cake, the said partition forming a compartment for the said lipstick unit and the said cosmetic cake, the said lipstick unit serving to position the cosmetic cake in the said casing compartment whereby the cosmetic cake may be contacted with the said applicator.
23. In a device of the class described, the combination of a casing having a closed bottom and provided with a powder compartment, a lipstick unit removably contained within the said casing, the said casing bottom being provided with a removable plug for gaining access to the said powder compartment, the said plug having an overhanging flange normally effective to retain the said lipstick unit in place in the said casing, a portion of the said flange being removed to form a flat surface whereby when the plug is turned to present the said flat surface to the lipstick unit, the latter may be removed from or inserted in the casing.
24. In a device of the class described, the combination of a casing open at one end, a closure member therefor, a member mounted in the casing for an extent of sliding movement, an element carried on the said slide member and movable therewith for propulsion from and retraction within the said casing, and an impositive connection between the said slide member and the closure member comprising a spring detent carried by the slide member and a detent depression provided in the closure member.
25. In a device of the class described, the combination of a casing and an applicator comprising a pair of hinged arms, a pleated fabric opposed side edges of which are secured to respective ones of the said pair of arms, and spring means tending upon the propulsion of the applicator from the casing to open the hinged arms to unfold the said fabric, the said pair of arms

being forced toward each other upon retraction of the applicator within the casing to fold the fabric to the confines of the casing.

26. As a new article of manufacture, an applicator comprising a pair of arms and a piece of fabric formed with pleats foldable upon each other, opposed side edges of which are secured to respective ones of the said pair of arms.

27. In a device of the class described, the combination of a casing open at one end, and an applicator propellable through the said opening comprising a pair of hinged arms and a fabric secured thereto, the pair of arms being formed of sheet metal bent to U-shape and forced together to grasp the edges of the fabric, the bend of the U-shaped arms providing a bearing surface for the arms on the edge of the said casing opening upon the propulsion and retraction of the applicator.

28. In a device of the class described, the combination of a casing open at one end, a slide guided in the casing, and an applicator propellable through the said opening and replaceably mounted on the said slide, comprising a pair of hinged arms and a fabric secured thereto, the proximal end of the arms being provided with opposed stud projections, and the said slide being provided with supports for the said pair of applicator arms, terminating in eyelets in which the said stud projections of the arms may be forced to pivotly and removably mount the said pair of arms of the applicator.

29. In a device of the class described, the combination of a casing open at one end, an applicator retractable in contracted condition within the said casing and propellable through the said opening in spread condition to present a flat cosmetic applying surface, at least one side of the said casing being tapered near the said open end in a direction toward the flat surface of the spread applicator.

30. In a device of the class described, the combination of a casing open at one end, an applicator propellable through the said opening and comprising a pair of hinged arms, the casing being provided with a pair of seats exterior of the said opening for respective ones of the said pair of arms, and spring means tending to spread the said pair of arms apart and in abutment with the said pair of seats, the said pair of arms being provided with recessed portions to form detent means with the said pair of seats to hold the applicator in propelled and spread condition.

31. In a device of the class described, the combination of a casing open at one end, a frame member in the form of an elongated U secured in the said casing with its bend at the said opening, an applicator propellable through the said casing opening and retractable in the casing be-

tween the legs of the frame member, one of the legs of the frame member serving as a partition to form a powder compartment, the said partition being provided with communicative means between the said powder compartment and the said applicator, a closure member for the casing opening, and a closure member for the powder communicative means, the second mentioned closure member being attached to the said applicator to move therewith, the said frame member being provided with a trackway for the said closure members.

32. In a device of the class described, the combination of a casing open at one end, a section of the casing serving as a cosmetic space and another section serving as an applicator space, a cosmetic cake provided in the said cosmetic space, and an applicator including a pleated fabric propellable through the said casing opening to present the said fabric unfolded as a flat cosmetic applying surface and retractable within the casing with the said fabric folded in the said applicator space of the casing and presenting the folds at the said cosmetic space of the casing, the said cosmetic cake being contactible with the said retractor applicator to apply cosmetic thereto.

33. In a device of the class described, the combination of a casing open at one end, an applicator retractable within the said casing and propellable through the said casing opening, a partition in the casing forming a powder compartment and provided with a plurality of holes communicative between the said powder compartment and the said applicator, and a valve plate provided with a plurality of holes corresponding to the said partition holes, the said valve plate being adjustable relative to the partition to regulate the effective opening through the said partition and valve plate holes.

34. A new article of manufacture for use in the device, including a casing and a cosmetic cake, of the class described, a lipstick or similar unit insertable in the said casing and adapted to maintain the said cosmetic cake in operative position.

35. In a device of the class described, the combination of a casing divided longitudinally into three sections, an applicator propellable from the top end of the casing and retractable in the middle section thereof, one of the outer sections being formed as a powder compartment and provided with means communicative with the retracted applicator, a rouge cake and a cosmetic unit such as a lipstick insertable in the other outer section from the bottom end of the casing, the cosmetic unit serving to maintain the rouge cake in operative position relative to the applicator and provided with a cosmetic element propellable from the said bottom end of the casing.

LEON H. AMDUR.
